UNITED STATES PATENT OFFICE.

HENRY W. CONARD, OF WYMORE, NEBRASKA.

FILE.

SPECIFICATION forming part of Letters Patent No. 630,487, dated August 8, 1899.

Application filed November 9, 1898. Serial No. 695,974. (No model.)

To all whom it may concern:

Be it known that I, HENRY W. CONARD, a citizen of the United States, residing at Wy-
more, in the county of Gage and State of Ne-
braska, have invented a new and useful File,
of which the following is a specification.

My invention relates to files adapted for
papers, letters, bills, &c., and particularly
designed for use in connection with railroad
accounts, to hold, in addition to letters and
bills, orders and papers giving rates of dif-
ferent kinds of freight and merchandise, in-
voices, general instructions, &c.; and the ob-
ject of the invention is to provide a file where-
in the papers are inclosed and concealed to
protect them from accumulations of dust, &c.,
the papers relating to any desired subject be-
ing readily accessible.

Further objects and advantages of this in-
vention will appear in the following descrip-
tion, and the novel features thereof will be
particularly pointed out in the appended
claim.

In the drawings, Figure 1 is a perspective
view of a file constructed in accordance with
my invention, the same being shown closed.
Fig. 2 is a similar view showing the file-case
open. Fig. 3 is a vertical sectional view. Fig.
4 is a detail view in perspective of the file-pin
holding and securing plate detached. Fig.
5 is a detail view of one of the index-card
holders. Fig. 6 is a detail sectional view to
show the means whereby the swiveled ele-
ments of the file-pins are mounted upon the
supporting-plate.

Similar numerals of reference indicate cor-
responding parts in all the figures of the draw-
ings.

The file embodying my invention consists,
essentially, of a base 1, from which rise front
and rear side walls 2 and 3 and end walls 4,
the end and rear walls being preferably fixed,
and a lid or cover 5, which is threaded and
movable upon the arched filing-pins 6 and is
flanged and rabbeted to engage the upper
edges of the side and end walls. The front
or outer side wall 2, or that which is remote
from the file-pins, is preferably hinged at its
lower edge to the base or bottom of the case
to fold outwardly, the same being secured in
its normal or closed position when the lid or
cover is in place by means of the overlapping

flanges of said lid or cover. Also in practice
I preferably employ front and rear catches 7,
arranged upon the side walls to engage the 55
contiguous edges of the lid or cover, said
catches being adapted for disengagement by
pressure to facilitate the opening of the case.

The file-pins, of which two are preferably
employed, consist of stationary or impaling 60
members 6^a, arranged within the space in-
closed by the walls of the case, and parallel
with and adjacent to the rear wall are mov-
able or arched members 6^b, of which the
shanks are swiveled to provide for turning the 65
arched extremities thereof laterally, where-
by papers engaged with the stationary or im-
paling members may be removed. The ex-
tremities of the swiveled or movable mem-
bers are provided with sockets to receive the 70
points of the stationary or impaling members.

In practice the cases may be made of dif-
ferent materials to suit the uses to which they
may be applied or the durability which they
must have in order to be serviceable; but I 75
prefer in the attachment of the file-pins to
employ a skeleton plate 8, secured to the base
or bottom of the case and having forwardly-
extending arms 9, from which the stationary
or impaling members of the file-pins rise 80
through the base or bottom of the box, and
rearwardly-extending arms 10, upon which the
shanks of the arched or movable members of
the file-pins are swiveled.

In the construction illustrated the shanks 85
of the arched or movable members of the file-
pins are shouldered to bear upon the upper
surface of the plate, and the reduced extremi-
ties of said shanks extend through suitable
bearings in the plate and are engaged by 90
screws 11.

Arranged upon the file-pins are movable
partitions or dividing-sheets 12, between
which and either loose or engaged with the
file-pins are arranged the papers which are 95
in the case, said partitions or sheets serving
to separate groups of papers and being prefer-
ably provided with index characters, whereby
they constitute indexing-sheets. I prefer-
ably employ pasteboard or equivalent ma- 100
terial for the indexing-sheets, and attached
thereto at the proper points are double-faced
holders 13, having flanged arms facing in op-
posite directions from the sheet and forming

seats for the reception of index-cards, which may be suitably inscribed and are removably fitted therein.

It will be understood that the lid or cover 5 may be turned back upon the shanks of the swiveled or arched members of the file-pins, together with such papers and indexing-sheets as may be above those papers to which access is desired, as indicated in Fig. 2, to 10 expose the desired sheets or papers and enable the operator to inspect the contents thereof without removing the same from the file-case, or, if required, the arched extremities of the movable members may be turned laterally to 15 expose the upper extremities of the stationary file-pin members, and thus allow the removal of the desired paper or papers.

Various changes in the form, proportion, and the minor details of construction may 20 be resorted to without departing from the spirit or sacrificing any of the advantages of this invention.

Having described my invention, what I claim is—

The herein-described file having a case 25 comprising a base, front, rear, and end walls, of which the front wall is hinged to fold outward, and a movable top or cover to engage the upper edges of said walls, a plate extending rearward from the base, and arched file-pins, having stationary members arranged in front of the rear wall, and swiveled members rising from said plate, with their shanks in rear of said rear wall, and having the top of the cover threaded thereon, and limited in its 30 rearward folding movement by said plate, substantially as specified.

In testimony that I claim the foregoing as my own I have hereto affixed my signature in the presence of two witnesses.

HENRY W. CONARD.
